UNITED STATES PATENT OFFICE

LEWIS L. CUNNINGHAM, OF MINNEAPOLIS, MINNESOTA, ASSIGNOR, BY MESNE ASSIGNMENTS, TO MINNEAPOLIS-HONEYWELL REGULATOR COMPANY, OF MINNEAPOLIS, MINNESOTA, A CORPORATION OF DELAWARE

AUTOMATIC SAFETY DEVICE

Application filed July 24, 1925. Serial No. 45,835.

This invention relates to new and useful improvements in thermally actuatable devices and more particularly to the provision of such a device including an element which may have a relatively greater effective expansion or distortion than its support, so that such relative heat distortion may be employed for operation and control of various means such as is common in this art, i. e. valves, dampers, electrical connections, etc.

Generally, the device includes a substantial ringlike portion and a transverse strip extending across said portion and terminally connected thereto, the strip being less thick than such portion and preferably having a section normally deformed or distorted from the normal plane or longitudinal axis of the strip so that when the strip is heated, it will bend in the general direction of such initial distortion or deformation.

The invention also comprehends a support for this strip and its enclosing portion so that these parts may be positioned adjacent a source of heat with the strip element more exposed to the heat than the enclosing portion whereby, upon heating the strip, the strip expands relatively to its enclosing portion and, upon cessation of heat the strip heat is conducted to the member. Preferably, the strip and its associated parts are integrally formed so that they will have the same co-efficient of expansion with the result that the relative effective expansion of these two parts will be substantially the same without regard to the initial temperature of the two parts.

The object of this invention is to provide an improved thermally actuatable device.

Other objects of the invention will appear from the following description and the accompanying drawings and will be pointed out in the annexed claims.

In the drawings, there has been disclosed a structure designed to carry out the various objects of the invention, but it is to be understood that the invention is not confined to the exact features shown as various changes may be made within the scope of the claims which follow.

In the accompanying drawings forming part of this specification,

Figure 1 shows a vertical sectional view through the device and a mounting upon a conventional representation of a heating plant and also showing electrical connections; 55

Figure 2 is a plan view of the preferred form of strip and integral arrangement;

Figure 3 is a top plan view of a portion 60 of the tubular mounting showing the position of the strip and ring in dotted lines;

Figure 4 is a view in vertical section showing the employment of two strips and rings and their electrical connections; and 65

Figure 5 is a cross-sectional view on the line 5—5 of Figure 4 showing the preferred arrangement of the strip when two are employed.

A selected form of the strip and connected support is shown in Figure 2 as consisting of a cross-sectionally thin strip 5 which extends diametrically across a cross-sectionally thick ring 6. The strip and ring are preferably of metal and are integrally formed. 70 A suitable metal is brass. As suggested in Figure 1, the ring is many times thicker than the strip. These parts are adapted to be mounted adjacent a source of heat so that the strip will be more exposed to the heat than the ring so that the strip will expand relatively to the ring, the heat-sensitive member 5 is herein shown integrally attached to the radiator or enclosing member or ring 6, substantially in a plane of one face of the radiator member, and diametrically thereof, the element 5 being thus offset in a direction axially of the annular member 6. Thus the enclosing member has its major portion 75 spaced from the member 5. In order that the strip may be distorted or bend in a predetermined direction, its major portion is given an initial distortion or deformation out of the former plane of longitudinal axis of the strip as is suggested in Figures 1 and 4. It is therefore obvious that when the strip is hotter than the ring, the strip will expand by continuing the usual distortion 80 rather than reversing the direction of dis-

85

100

tortion so as to pass through the normal plane or axis of the strip.

A mode of using this novel thermally actuable device is shown in Figure 1 where-
in there is employed an elongated hollow
member such as the cylinder 7, adapted to
be supported adjacent a source of heat, such
as the boiler 8 containing any of the usual
forms of heating means. This cylinder 7
is flanged or provided with lugs 9 whereby
the cylinder may be securely bolted to the
walls of the boiler surrounding an aperture
therein through which the cylinder 7 ter-
minally projects. This boiler or furnace
end of the cylinder 7 is open so that heat
may pass within the cylinder by radiation
and possibly by convection. The transverse
strip 5 is placed diametrically across the
outer end of the cylinder 7 and the oppo-
site portions of the outer edge of the cyl-
inder are preferably provided with recesses
10 to receive the end portions of the strip
(see Fig. 3). The ring 6 is given an inner
diameter which makes a close fit with the
periphery of the cylinder cover 11.

One means for using this relative ex-
pansion of the strip and its ring is shown in
Figure 1 wherein a threaded stem 12 is
borne by the strip in insulated relation there-
from.

The particular form of mounting shown
consists of a flanged plug 13 of insulating
material which tightly fits the central aper-
ture 14 in the strip, with the flange of the
plug resting against the adjacent face of
the strip. A nut 15 is mounted on the stem
12 and a washer 16 is interposed between
this plug and nut. A washer 17 of insulat-
ing material abuts against the inner face of
the strip adjacent the aperture 14 and its
inner face is partially covered by a metallic
washer 18 and the parts are held in as-
sembled relation by means of a nut 19 se-
cured in threaded engagement with the stem
45 12 whereby movement of the strip is com-
municated to the stem 12. The stem 12 pro-
jects through an aperture in the cover 11
and has an electrical wire 20 terminally car-
ried thereby. The other end of this wire
50 20 is connected to a binding post 21 which
extends through an insulated plate 22 for
electrical connection with the control wire
23. The other control wire 24 is connected
to a binding post 25 inwardly extending in
55 spaced relation through the insulating plate
22 and terminating in a contact point 26
normally in spaced relation from the con-
tact head 27 carried on the outer end of the
stem 12. The insulating plate 22 is screwed
60 to angled brackets 30 which are also screwed
to the ring 6.

When combustion takes place within the
boiler 8, such for example, as the flame
of an oil burning apparatus, heat is directed
65 to the transverse strip 5 within the tube 7.

At the initiation of such heat the strip and
ring are substantially at the temperature
of the surrounding atmosphere regardless
of the number of degrees. The strip 5, be-
ing more or less directly heated, expands 70
and is distorted in the direction of its ini-
tial deformation so that the stem 12 is out-
wardly pushed to effect electrical engage-
ment of the head 27 and contact point 26
with the resultant closure of any electrical 75
control circuit provided by the wires 23 and
24. Upon cessation of the heat, the heat of
the strip 5 is conducted to its integral ring
6 so that the parts assume their relatively
normal relationship whereby the electric 80
contact between the head 27 and the point
26 is opened in order to reduce the conduc-
tion of heat between the strip and its ring,
the ends of the strip adjacent the ring are
preferably reduced as shown in Figure 2. 85

In the form shown in Figure 4, there are
employed two such rings and strips simi-
larly carried by the tube 7. The additional
similar ring 28 occupies a position reversed
with respect to that of the complementary 90
ring 6, with the result that the initial dis-
tortion of its integral transverse strip 29 is
toward that of the strip 5. By this means
there is provided substantially twice the
relative movement obtainable by the use of a 95
single strip. The stem 12 is carried by the
strip 5 in the same manner as shown in Fig-
ure 1, but an insulating sleeve 31 is fixedly
carried by the strip 29 and the stem 12
passes longitudinally through the sleeve 31. 100
The outer end of the stem 12 projects be-
yond the sleeve 31 and is connected to the
wire 23 and terminally provides the con-
tact head 27. A bracket 32 of insulating
material, is fixedly carried by the sleeve 31 105
and outwardly extends beyond the end of
the stem and its offset arm 33 is apertured
to support the binding post 25, electrically
connected to the wire 24 and inwardly pro-
jecting to provide the complementary con- 110
tact point 26 for the contact head 27. When
these strips are heated, the strip 5 continues
its initial distortion and its central portion
outwardly bends, and the strip 29 likewise
continues its initial distortion and inwardly 115
bends. The result is, that the stem 12 is
outwardly thrust while the sleeve (which
carries the bracket 32 and binding post and
contact 26) is inwardly thrust so that the
contact head 27 and contact point 26 are 120
moved to electrical engagement. Upon re-
moval of the source of heat supply, the cool-
ing of the strips 5 and 29 causes them to
move apart with the resultant moving apart
of the head 27 and contact point 26 and
interruption of the previously formed cir-
cuit at these points. Preferably, when two 125
strips are used, they are positioned at right
angles in the tube as shown in Figure 5
in order that each may attain the maximum 130

expanding effect of the heat directed to the tube.

Having thus described my invention what I claim as new and desire to secure by Letters Patent, is:

1. A device of the class described comprising a tubular member, an annular element encircling said tubular member and having a relatively large cross-section, a relatively thin heat-sensitive element enclosed by the tubular member and attached to said relatively thick annular element, and a cap closing the tubular member and having a sealing socket fitted within the annular element.

2. A tubular element having a closed end, an annular element encircling and embracing the tubular element and having a relatively thin heat-sensitive element enclosed by the tubular element, and said heat-sensitive element carrying an electrical contact which slidably traverse the closed end, and a second contact with which said first contact is cooperative when the heat-sensitive element is deflected.

3. A device of the class described comprising a tubular element, an annular element encircling and embracing the tubular element and having a heat-sensitive element enclosed by the tubular element, the annular and heat-sensitive elements having the same co-efficient of expansion and being integral and being disposed intermediately of the ends of the tubular element, the said heat-sensitive element being cross-sectionally thinner than the annular element.

4. A tubular element having a closed end, an annular element encircling and embracing the tubular element, and having a relatively thin heat-sensitive element enclosed by the tubular element, and said heat-sensitive element carrying an electrical contact which slidably traverses said end, and a second contact supported by the annular element with which said first contact is cooperative when the heat-sensitive element is deflected.

5. A tubular element having a cap closing one end, an annular element encircling and embracing the tubular element and cap and having a relatively thin heat-sensitive element enclosed by the tubular element, and said heat-sensitive element carrying an electrical contact which slidably traverses said end, and a second contact with which said first contact is cooperative.

6. An elongated tubular element having a cap closing one end, an annular element encircling and embracing the tubular element and cap and having a relatively thin heat-sensitive element enclosed by the tubular element adjacent the cap, said heat-sensitive element carrying an electrical contact which slidably traverses said cap, and a second contact supported by the annular element

with which said first contact is cooperative when the heat-sensitive element is deflected.

7. A thermally actuatable device comprising a tubular element, a pair of annular elements encircling and embracing the tubular element, each element having a heat-sensitive element enclosed by the tubular element, the said heat-sensitive elements being spaced within the tubular element, said elements having the same co-efficient of expansion as their respective annular elements and being integral therewith.

8. A thermally actuatable device comprising a tubular element, an annular element encircling and embracing the tubular element, and having a relatively thin heat-sensitive element enclosed by the tubular element, said element having the same co-efficient of expansion as its annular element and being integral therewith, said annular and heat-sensitive element being located intermediately of the ends of the tubular element.

9. A thermally actuatable device comprising a tubular element, a pair of annular elements encircling and embracing the tubular element, each element having a relatively thin heat-sensitive element enclosed by the tubular element, an electric contact carried by one of the heat-sensitive elements, a tubular member of insulating material connecting with the other element and slidably upon the first, said insulating element carrying a contact cooperable with the first mentioned contact.

10. A device of the class described comprising a hollow member, a heat conducting element attached crosswise within the member, and having an annular thickened portion exposed at the outer side of the member as a conductor and radiator of heat.

11. A device of the class described comprising an elongated tubular element, a relatively thin element of heat conducting material arranged within and crosswise of said tubular element, and having a portion exposed at the outside of said tubular element and of a cross-sectional area to cause a predetermined quantity of received heat to be continually radiated and dissipated from within.

12. A device of the class described comprising a hollow member, a heat conducting element attached crosswise within the member, and having a thickened annular portion exposed at the outer side of the member as a conductor and radiator of heat, that end of the tube nearest the heat conducting element being closed, whereby a greater temperature can be maintained inside than outside of said member, and whereby heat received by said heat conducting element is continually radiated and dissipated outwardly.

13. A device of the class described com-

prising a tubular member, an element of heat conducting material arranged within and crosswise of said member to intercept heat traveling within the member, and having a portion exposed at the outside of the member and acting as a radiator, whereby a predetermined quantity of heat received by said inner element can be continually radiated and dissipated at the outside of the tubular member.

14. A device of the class described comprising a tubular member, a relatively thin element of heat conducting material arranged within and crosswise of said member to intercept heat traveling within the member, and having a portion exposed at the outside of the member of a cross-sectional area substantially greater than the relatively thin element, whereby a predetermined quantity of heat received by said relatively thin element can be continually radiated and dissipated at the outside of the tubular member.

15. A device of the class described comprising a tubular member, an element arranged within the member and having a portion exposed at the outer side of the member and of such cross-sectional area as to cause it to act as a comparatively rapid radiator and dissipater of heat received by the inner element, the said member being closed at a point adjacent the inner element.

16. A device of the class described comprising a tubular member, an element arranged within the member and having a portion exposed at the outer side of the member and of such cross-sectional area as to cause it to act as a comparatively rapid radiator and dissipater of heat received by the inner element, the said member being closed at one end only and said element being arranged at a point adjacent the closed end.

17. A device of the class described comprising a hollow member, a heat conducting element exposed at the outside of the member and a second heat conducting element arranged within the member crosswise thereof and connected with the first mentioned heat conducting element, said elements being arranged at a point intermediately the ends of the hollow member.

18. A device of the class described comprising a hollow member, a heat conducting element exposed at the outside of the member and a second heat conducting element arranged within the member crosswise thereof and connected with the first mentioned heat conducting elements, said elements being arranged at a point intermediately the ends of the hollow member, and said member being closed at one end.

19. A radiator element, a heat sensitive element connected thereto, and a shield arranged to allow impingement of heat energy

upon the heat-sensitive element in greater degree than upon the radiator element.

20. A radiator element, a heat-sensitive element connected thereto, and a shield arranged so that a difference in temperature between the elements can be maintained such that the heat-sensitive element will have the higher temperature.

21. A radiator element, a heat-sensitive element connected thereto, and a shield arranged to regulate the degree of impingement of radiant energy upon the elements so that the radiator element can never be raised to a temperature equal to that of the heat-sensitive element.

22. In combination with a heating device having an opening through which radiant energy can pass from within outwardly, a radiator element outside the heating device, a heat-sensitive element connected with the radiator element and arranged to be affected by radiant energy passing through the opening, and a shield arranged to permit direct impingement of radiant energy upon the heat-sensitive element but protect said radiator element from such direct impingement.

23. A radiator element, a heat-sensitive element connected thereto, and arranged so that a difference in temperature between the elements can be maintained so that the heat-sensitive element will have the higher temperature.

In witness whereof, I have hereunto set my hand this 13th day of July, 1925.

LEWIS L. CUNNINGHAM.
